UNITED STATES PATENT OFFICE.

EDWIN F. KINGSBURY, OF COLWYN, PENNSYLVANIA, ASSIGNOR TO THE UNITED GAS IMPROVEMENT COMPANY, OF PHILADELPHIA, PENNSYLVANIA, A CORPORATION OF PENNSYLVANIA.

FLICKER ATTACHMENT FOR PHOTOMETERS.

1,176,466.

Specification of Letters Patent. Patented Mar. 21, 1916.

Application filed June 7, 1915. Serial No. 32,539.

To all whom it may concern:

Be it known that I, EDWIN F. KINGSBURY, a citizen of the United States, residing at Colwyn, Delaware county, Pennsylvania, have invented a certain new and useful 5 Flicker Attachment for Photometers, of which the following is a specification.

An equality of brightness photometer is extensively and satisfactorily used where the 10 color of the sources of light is substantially the same. However, where the color of the sources of light is different, a flicker photometer is most appropriate. Although these instruments have many parts in common, it has been customary to construct them 15 as separate instruments throughout so that the custom has been to provide and employ two complete photometers, one of the flicker variety and the other of the equality of brightness variety, and this entails considerable expense, trouble and annoyance.

The principal object of the present invention is to provide for economically making one type of photometer do the work of two 20 and operate either by equality of brightness or by the flicker method as may be required.

Another object of the invention is to provide a flicker attachment which shall be comparatively inexpensive and efficient and 25 which can be conveniently interchanged with the telescope of an equality of brightness photometer and which, when so interchanged, converts the device into a flicker photometer.

The invention will be claimed at the end 30 hereof but will be first described in connection with the embodiment of it in a Lummer-Brodhun contrast photometer, although it can be embodied in other types of well known photometers, the Lummer-Brodhun 35 type being selected merely for illustration in the accompanying drawings in which—

Figure 1, is a perspective view of so much of a Lummer-Brodhun contrast photometer 40 as is necessary to illustrate the application of my invention thereto. Fig. 2, is a transverse sectional view illustrating a flicker attachment embodying features of the invention. Fig. 3, is a diagrammatic sectional 45 plan of the photometer proper. Fig. 4, is a diagram of the Lummer-Brodhun contrast photometer field, showing also the method by which the flicker attachment utilizes the same, and Fig. 5, is a view similar to Fig. 4,

but showing another type of equality of brightness photometer field.

Although I shall describe the invention in connection with the Lummer-Brodhun type of contrast photometer, the invention is not limited to that type as there are other well known types of equality of brightness photometers to which it is applicable.

In the drawings 1, is a tube adapted to replace and to be interchangeable with the ordinary telescope of an equality of brightness photometer. At one end of this tube there is arranged a magnifying lens 2, and at the other end the lens 3, of the eye-piece. The lens 2, is mounted in the carrier inserted in the end of the tube 1, and the lens 3, is mounted in one end of a second tube 4, inserted in the first tube 1, and constituting in effect a continuation thereof. The prism 5, is mounted in a spool-like structure 6, revolvably mounted in a ring bearing 7, arranged within the tube 1, and held to place by a set screw 8.

9, is an oil hole.

The flanges of the spool-like structure 6, operate as collars and prevent end play of 80 the structure in its bearing ring while permitting the structure to rotate freely.

10, is a belt advantageously of the coiled wire or spring variety and it connects the pulley 11, on the structure 6, with the pulley 85 12, of a motor 13, shown as of the electric variety.

14, is a spring brake arm carried by a bracket 15, and adapted to be made to press upon the pulley 12, or some part thereof, 90 with more or less pressure by means of the adjusting screw 16, carried by the bracket 15, so as to afford control of the speed of the motor and of the speed of rotation of the prism.

95 17, is a centrally apertured disk or partition arranged at the inner end of the tube 4.

100 Mounted on the tube 4, so as to be turnable thereon is a lighting fixture 18, consisting of a collar encircling the tube and an open ended chamber 19, in which the lamp or light is arranged. There is an opening 20, in the tube 4, the effective size of which can be varied by turning the fixture 18, and in this way the extent or degree to which the interior of the eye-piece is illuminated 105 can be varied. The function of the light-

ing fixture is to supply, as shown from an electric lamp, light for the purpose of illuminating the whitened interior of the tube 4, and more particularly the surface of the partition or disk 17, nearest the eye so as to avoid excessive strain on the eye such as would occur if the surface were dark and a light spot were viewed.

From the foregoing description it is evident that the attachment consists of a single piece and that the lenses and various parts can be readily removed and replaced.

In further describing the invention reference will be made to the Lummer-Bredlun contrast photometer, the box 21, of which is provided with an opening 22, that detachably receives the described attachment and that received the ordinary telescope which is not shown but is well understood. The arrows 23 and 24, indicate rays of light from the respective sources in their passage through the box and in respect to the reflecting surfaces thereof and to the device 25, by which they are brought into juxtaposition. To apply the attachment of my invention to the box 21, the telescope and its contrast glasses are removed and the attachment applied in the manner described and when so applied it is evident that there is provided a flicker photometer in connection with which the ordinary box 21, and its accessories are utilized.

Referring to Fig. 4, 26, indicates the field of light presented to the eye by one source of light, and 27, represents the field of light presented to the eye by the other source of light. This is the condition of affairs when the flicker attachment is not present. When the attachment is in operation the field presents nothing but a small illuminated circle which travels in a circular orbit 29. As the prism revolves, the circular field 28, travels around in its circular orbit 29, and its brilliancy and color vary as it travels, or in other words, it flickers until the brilliancy of those portions of the fields of light 26 and 27, traversed by the circle become equal whereupon the field 28, ceases to flicker and has but one color. The construction and mode of operation of the arrangement shown in Fig. 5, is the same as in Fig. 4, except that the fields 26^a and 27^a, are of different shape.

It will be obvious to those skilled in the

art to which the invention relates that modifications may be made in details of construction and arrangement without departing from the spirit of the invention which is not limited as to those matters nor further than the appended claims and the prior state of the art may require.

What I claim is:

1. A flicker attachment for equality of brightness photometers which consists of a sight tube interchangeable with the telescope of such photometers and provided with lenses and a rotary prism and an apertured diaphragm and adapted for detachable application to such photometers, substantially as described.

2. A flicker attachment for equality of brightness photometers consisting of the combination of a tube having a lateral opening, a prism revolvably mounted in the tube, lenses and an apertured diaphragm mounted in the tube, and a lighting fixture revolvably mounted in the tube and provided with a light and an open ended lighting chamber which can be brought into varying alignment with said lateral opening, substantially as described.

3. The combination of an equality of brightness photometer, a detachable sight tube having a prism arranged therein, and means for rotating the prism, substantially as described.

4. The combination of an equality of brightness photometer and a detachable sight tube having a prism revolvably mounted therein.

5. The combination of an equality of brightness photometer, a detachable sight tube having a prism revolvably mounted therein, a motor, a spring belt between the motor and prism, a brake for the motor, and a set screw for adjusting the brake, substantially as described.

6. A flicker attachment for equality of brightness photometers consisting of a sight tube, a ring mounted therein, a spool-like structure revolvably mounted in the ring and provided with a prism, and lenses and an apertured diaphragm mounted in said tube, substantially as described.

EDWIN F. KINGSBURY.
